SKI TRIMMING LOCK

William Armstrong, New York, N. Y., assignor to
The Dowty Corporation, Wilmington, Del., a
corporation of Delaware

Application February 15, 1940, Serial No. 319,073

6 Claims. (Cl. 244—108)

This invention relates to a ski trimming lock and more particularly to such a lock on a ski which is mounted on the airplane with what is known as levered suspension.

The principal object of the present invention is to provide a ski trimming lock controlled by compression and extension of the suspending lever upon which the ski is pivotally mounted; when the lever is compressed under the weight of the airplane upon the ski, the locking means is automatically unlocked so that the ski is free to pivot while the airplane is on the ground. When the airplane takes off, the extension of the lever of the lever suspension automatically causes locking of the ski in a predetermined position parallel to the plane of flight.

Another object is to provide a ski lock of the foregoing type wherein what is known as parallel leverage suspension of the ski is employed.

Another object is to provide a ski trimming lock of the foregoing type which is simple to construct, inexpensive to manufacture, light in weight, which presents a minimum of air resistance, which is inexpensive to maintain, and which operates very effectively to positively lock the ski against fluttering or pivoting during flight and automatically unlocks the ski for free pivotal movement upon engagement of the airplane with the earth, said pivotal movement being restrained within limits.

Other objects of the present invention will more fully hereinafter appear.

Reference is made to my copending applications, Serial Nos. 319,072 filed Feb. 12, 1940, and 319,074, filed Feb. 15, 1940, which disclose ski trimming locks embodying principles related to the present application.

In the accompanying drawings:

Fig. 1 is a side elevation of an airplane equipped with a leverage suspension ski provided with one form of locking device embodying the principles of the present invention. This figure shows the airplane on the ground with its tail down.

Fig. 2 is a fragmentary vertical section of the locking mechanism of Fig. 1. This view shows the ski locked, the airplane being in flight.

Fig. 3 is a similar view showing the device when the airplane is on the ground with the tail up and there is no deflection of the ski relative to the surface of the ground.

Fig. 4 is a side elevation of the device of Figs. 1 to 3 showing it as the airplane is on the ground with the tail down and with no deflection of the ski.

Fig. 5 is a rear view of Fig. 4.

Fig. 6 is a view similar to Fig. 4 showing the device with the tail down and with the ski tilted so as to elevate its front end. This view may be construed as illustrating an airplane taking

off and encountering an obstruction in the surface of the earth which throws the front end of the ski upwardly.

Figs. 7 and 8 portray a modification, Fig. 7 showing the modified form with the ski locked in flight and Fig. 8 showing it in unlocked position with the tail of the airplane down.

Figs. 9 and 10 portray another modification in which what is known as parallel levered suspension of the ski is employed. In these views, Fig. 9 shows the mechanism locked in flight and Fig. 10 shows the mechanism as it appears when the airplane is on the ground with the tail down and with no deflection of the ski.

Figs. 11 and 12 portray still another modification in which parallel lever suspension is used. In these views, Fig. 11 shows the device locked in flight while Fig. 12 shows the device unlocked with the airplane on the ground with its tail down and with no deflection of the ski.

Referring to the drawings in detail and to the embodiment illustrated in Figs. 1 to 6, 1 designates the body of an airplane having a wing 2 from which there depends a fixed strut 3. No attempt is made to illustrate the construction of the strut 3 other than diagrammatically since its construction is well within the skill of the art, it being sufficient to state that the strut 3 is carried by the airplane and depends downwardly therefrom. Strut 3 may be rigidly carried by the airplane or yieldingly or pivotally mounted thereon. At the lower end of strut 3, there is pivotally mounted the rearwardly extending lever 4 which is adapted to swing up and down relative to strut 3. Pivotally mounted on the rearward end of lever 4 is the ski 5 which has the pedestal 6 which is pivotally engaged with the rear end of lever 4, as by means of the pivot pin 7.

Arranged between strut 3 and lever 4 is a shock absorber, one form of which is diagrammatically illustrated as comprising the cylinder 8 fixedly carried in the lower end of strut 3, the spring 9 and the piston 10 having the port 11 which is adapted to allow air under pressure to pass from above piston 10 to a point therebelow. Fixedly carried by the piston 10 is rod 12 which extends downwardly into pivoted relationship with lever 4 by means of a pivot pin 13.

The ski locking device comprises the locking pin 14 rigidly carried by the rearwardly extending ears 15 which are rigidly mounted in any suitable manner upon the exterior of strut 3. Cooperatively associated with the locking pin 14 are the upwardly extending locking plates 16 which are rigidly secured to the ski 5 in any desired manner, as for example by welding to the pedestal 6. The locking pin 14 is received within the slot or opening in the locking plates 16.

The opening in the locking plates 16 is designed to allow considerable pivotal movement of the ski 5 relative to the strut 3 when the weight of the airplane is on the ski, and to automatically lock these elements against relative pivotal movement when the airplane leaves the earth. The opening has the relatively wide portion extending between the points 17 and 18 and the locking portion 19. Points 18 and 19 are connected by the rear guide wall 20 which is shown as taking the form of a straight line extending between points 18 and 19 but which obviously may be curved or arcuate provided it is of such a configuration as to guide the pin 14 along it into the locking space 19. The points 17 and 19 are connected by the upper front wall 21 which comprises the upwardly curved portion 23 which leads to the inwardly curved shoulder portion 22 closely adjacent the locking portion 19, and which is adapted to similarly guide pin 14 into portion 19 when the airplane takes off. If desired, the upper wall 21 may be a straight line similar to the upper wall 20.

The opening in the locking plate 16 extends downwardly below the widest portion in order to provide for reception of the pin 14 in case an unusually violent shock is encountered in taking off or landing. As shown, the lower portion of the slot comprises the lower straight rear wall 24, and the lower arcuate front wall 25, these being connected through the intermediary of the portion 26.

The provision of the convex curve 23 followed by the concave portion 22 causes the locking pin 14 which is normally moving around in the forward half of the locking slot during taking off to be moved into the locking portion 19 with a snap as it passes over shoulder 22. This adds somewhat to the sureness of the lock and tends to prevent the locking pin from becoming disengaged from its locking position during flight due to the action of wind upon the front end of the ski.

The operation of the device of Figs. 1 to 6 will be obvious from the foregoing and from the drawings but may be stated briefly as follows:

Upon elevating the tail of the airplane preparatory to taking off, the parts assume the position shown in Fig. 3, the weight of the airplane having compressed the spring 9 of the shock absorber and having caused thereby the locking pin 14 to move downwardly into substantially the widest portion of the slot. During the take-off, the ski is free to move through an angle of at least 15° in either direction about its pivot point. Should an obstruction be encountered during the take-off which causes the front of the ski to rise, the locking plate 16 will be turned so as to move the pin 14 into the forward half of the slot. As the take-off is completed, the locking pin 14 has moved upwardly so as to engage one of the surfaces 20 or 21 and be guided thereby into the locking portion 19 by reason of the expansion of the spring 9 of the shock absorber.

Upon landing, when the skis engage the ground, the spring 9 will be instantaneously compressed somewhat by the weight of the airplane and will immediately force the locking pin 14 downwardly from its locking recess 19. If the landing is with the tail down, the pin will move in a curved path to the position shown in Fig. 4. If the landing is with the tail up, it will move to the position shown in Fig. 3. Thereafter, it will move around in the slot allowing the ski to pivot freely within limits set by the sides of the slot

so as to accommodate itself to the terrain during the landing.

Modification of Figures 7 and 8

In Figs. 7 and 8, there is shown a modification of the embodiment of Figs. 1 to 6. In the modified form of the device, the only difference is that the location of the locking plate and of the locking pin is interchanged, the locking plate 27 being rigidly mounted on the side of the strut 3 and the pin 28 being rigidly mounted between two ears 29 which are rigidly mounted upon or integral with the pedestal 6 of the ski 5. The slot in the locking plate 27 comprises the locking portion 30, the slanting front wall 31 and the slanting front wall 32. The wall 31 is adapted to engage the pin 28 when the rear of the ski is elevated while the wall 32 which has a greater angle to allow for sufficient freedom of movement when the tail is down is adapted to engage the pin 28 when the front of the ski is elevated. The slanting walls 31 and 32 cooperate with the locking recess 30 to guide the locking pin 28 into this recess when take-off has been completed. The upper relatively wide portion of the slot comprises the arcuate walls 33 and 34 and the flat connecting portion 35. It will be apparent that the portion of the slot which is occupied chiefly by the pin 28 will be that portion lying between points 36 and 37. The operation of the device is the same as that for the embodiment shown in Figs. 1 to 6.

Modification of Figures 9 to 12

In Figures 9 to 12, there is illustrated the use of a ski which is supported by what is known as parallel lever suspension. The strut supported by the airplane in any desired manner is designated 38 and has pivotally mounted at its lower end the rearwardly extending lever 39 which has the ski 5 pivotally mounted adjacent its rear end by means of the pin 40. The lever 39 extends beyond the pin 40 in an upwardly curved portion 41. A shock absorber is disposed between this curved portion 41 and the strut 38, this shock absorber comprising the barrel 42 which is pivotally mounted to the strut 38 at 43. The shock absorber also comprises the telescoping rod 44 which engages mechanism not shown within the barrel 42 which is adapted to yieldingly allow compression of rod 44 within barrel 42 and to normally urge rod 44 rearwardly out of barrel 42. The rod 44 is pivoted to the upper end of the rear tip 41 of lever 39 as at 45.

Describing now the locking device of Figs. 9 and 10, this comprises the locking plates 46 which are rigidly mounted on the ski 5 as by welding to the pedestal 6. The locking device further comprises the pins 47 which extend laterally on each side of the barrel 42 and which are rigidly carried by the barrel 42. The slot in the locking plate 46 is designed as before with a locking recess 48 and with guide walls 49 and 50 which converge into the locking portion 48. The operation of the device is essentially the same as the operation of the device shown in Figs. 1 to 6, the guide walls 49 and 50 serving to guide the pin 47 into the locking recess 48 and the relatively wide portion below the guide walls 49 and 50 serving to accommodate the pin 47 during landing and take-off.

In Figs. 11 and 12, the disposition of the locking plate and the locking pin is reversed, the locking plates 51 being rigidly mounted on barrel 42 of the shock absorber and the locking pin 52

being rigidly carried by the ski 5 by means of the ears 53 which are integral with the pedestal 6. The pin 52 is adapted to be held within a locking portion 54 of the slot in plate 51. The pin 52 is adapted to be guided into this locked position by the guide walls 55 and 56 which converge into the locking portion 54. The operation is identical with that described for Figs. 9 and 10.

From the foregoing, it will be seen that the present invention provides a locking device which is economical to build, simple in operation and light in weight. The device operates positively and reliably to lock and unlock the ski as take-off and landing occur. The device offers a minimum of air resistance although if desired fairing of any suitable type may be provided around the device.

I wish it to be understood that I intend to include as within the invention such modifications as may be necessary to adapt it to varying conditions and uses and as fall within the terms or spirit of the appended claims.

Having thus fully described my invention, what I claim as new and desire to secure by Letters Patent is:

1. In an airplane landing gear, a strut carried by the airplane, a lever pivoted at one end to said strut, a ski pivotally mounted at the other end of said lever, shock absorber means interposed between said strut and said lever and tending normally to move said lever and thereby said ski downwardly, and a trimming lock for said ski, said lock comprising a slotted locking plate member and a cooperating locking pin member received in the slot in said plate, the slot in said plate member having a locking portion adapted to receive said pin member and to thereby lock said ski, one of said locking members being carried by said strut and the other of said locking members being rigidly carried by said ski.

2. In an airplane landing gear, a downwardly extending strut carried by the airplane, a lever pivotally mounted at one end to said strut, a ski pivotally mounted on the other end of said lever, shock absorber means interposed between said strut and said lever and tending normally to move said lever and thereby said ski downwardly, locking means for locking said ski in flight comprising a slotted locking plate member and a locking pin member received in the slot in said plate, one of said members being carried on said strut and the other of said members being rigidly carried on said ski, said slot comprising a relatively wide portion adapted to receive said pin member and allow relatively great pivoting of said ski when the weight of the airplane is on the ski, a relatively narrow locking portion adapted to lockingly receive said pin member when the airplane is in flight, and side walls converging from said wide portion to said locking portion for guiding said pin member into said locking portion as the airplane takes off.

3. In an airplane landing gear, a strut carried by the airplane and extending downwardly therefrom, a lever pivotally mounted at one end on said strut, a ski pivotally carried by said lever, shock absorber means carried between said lever and said strut, and locking means for locking said ski comprising a slotted locking plate

carried by said strut and a cooperating locking pin rigidly carried by said ski and received within the slot of said plate, said slot comprising a relatively wide portion adapted to accommodate said pin freely within limits when the weight of the airplane is on the ski, a relatively small locking portion adapted to lockingly receive said pin when the airplane is in flight, and inclined side walls converging from said wide portion to said locking portion for guiding said pin to said locking portion as the airplane leaves the earth.

4. In an airplane landing gear, a strut carried by the airplane and depending downwardly therefrom, a lever pivotally mounted at one end to said strut and adapted normally to lie at an angle thereto, shock absorber means interposed between said strut and said lever and normally tending to urge said lever downwardly, a ski pivotally mounted on the other end of said lever, and locking means for said ski comprising a slotted locking plate rigidly carried on said ski and a locking pin carried by said strut and received in the slot in said plate, said slot in said plate having a locking portion on the side thereof away from said ski and side walls converging away from said ski towards and into said locking portion for guiding said pin into said locking portion as the airplane leaves the earth.

5. In an airplane landing gear, a strut carried by the airplane, a lever pivotally mounted at one end on the lower end of said strut, a ski pivotally mounted on the other end of said lever, a shock absorber telescopically associated with said strut and interposed between said strut and said lever, and means for locking said ski in flight comprising a slotted locking plate member and a locking pin member received in the slot of said plate member, one of said members being rigidly mounted on said strut and the other of said members being rigidly mounted on said ski, the slot in said plate having a relatively wide portion and a narrow locking portion and having sides gradually converging from said relatively wide portion to form said narrow portion.

6. In an airplane landing gear, a strut depending from the airplane, a lever pivotally mounted thereon and adapted to normally lie at an angle thereto, a ski pivotally mounted on the other end of said lever, shock absorber means extending generally parallel to said lever and having one of its elements pivotally connected to said strut and the other of its elements pivotally connected to said lever, said shock absorber normally tending to move its elements apart, and locking means for locking said ski in flight comprising a slotted locking plate member and a locking pin member in the slot of said plate member, one of said members being rigidly carried by said element connected to said strut and the other of said members being rigidly carried by said ski, said slot comprising a relatively wide portion adapted to accommodate said pin member when the weight of the airplane is on the ski within relatively great limits of freedom, a locking portion on the side away from the member on which said plate member is carried, and converging side walls leading from said wide portion to said locking portion.

WILLIAM ARMSTRONG.
